COMBINED MOTOR VEHICLE LIQUID AND CUP DISPENSER

Howard Cooper Johnston, St. George, S. C.

Application June 2, 1955, Serial No. 36,334

Term of patent 14 years

(Cl. D2—3)

Fig. 1.

Fig. 3.

Fig. 2.

Fig. 1 is a front perspective view of a combined motor vehicle liquid and cup dispenser embodying my new design.

Fig. 2 is a reduced side elevation looking from lefthand side of Fig. 1, and

Fig. 3 is a plan view of the dispenser as shown in Fig. 2.

The rear and the side of the combined motor vehicle liquid and cup dispenser opposite that shown in Figs. 1 and 2 are substantially plain.

I claim as my invention:

The ornamental design for a combined motor vehicle liquid and cup dispenser, substantially as shown and described.
